UNITED STATES PATENT OFFICE

167,986

TIE HANGER

Alfred S. Jonaitis, New York, N. Y.

Application March 1, 1952, Serial No. 18,747

Term of patent 7 years

(Cl. D33—8)

To all whom it may concern:

Be it known that I, Alfred S. Jonaitis, a citizen of the United States, residing at 235 East 52nd Street, New York city, county and State of New York, have invented a new, original, and ornamental Design for a Tie Hanger, of which the following is a specification, reference being had to the accompanying drawing, forming part thereof, and in which:

Figure 1 is a front elevational view of a tie hanger, showing my new design.

Figure 2 is an end elevational view of the same; and

Figure 3 is a top plan view thereof.

I claim:

The ornamental design for a tie hanger, as shown.

ALFRED S. JONAITIS.
